UNITED STATES PATENT OFFICE.

ELIAS F. SLEAR, OF COLLINGSWOOD, NEW JERSEY.

TOY FIREARM.

1,286,437.

Specification of Letters Patent.

Patented Dec. 3, 1918.

Application filed April 2, 1918. Serial No. 226,154.

To all whom it may concern:

Be it known that I, ELIAS F. SLEAR, a citizen of the United States, and a resident of Collingswood, county of Camden, and 5 State of New Jersey, have invented a certain new and novel Toy Firearm, of which the following is a specification.

The principal object of the present invention is to provide a toy symbolic of a gun or 10 pistol which may be cheaply manufactured so as to serve as an advertising medium. A further object of the present invention is to provide a toy of the character stated which while possessing the advantages of resembling 15 a gun or pistol is harmless in operation so that a child may use the same in safety.

The invention consists of the improvements hereinafter described and finally claimed.

20 The nature, characteristic features and scope of the invention will be more fully understood from the following description taken in connection with the accompanying drawings forming part hereof and in which:

25 Figure 1 is a view in side elevation of the toy firearm embodying features of the invention, in position for operating.

Fig. 2 is a top or plan view thereof, and

30 Fig. 3 is a view in side elevation showing the position of parts when operated.

For the purpose of illustrating my invention, I have shown in the accompanying drawings one form thereof which is at present preferred by me since the same has been 35 found in practice to give satisfactory and reliable results, although it is to be understood that the various instrumentalities of which my invention consists can be variously arranged and organized and that my invention 40 is not limited to the precise arrangement and organization of the instrumentalities as herein shown and described.

For illustrative purposes, a firearm symbolic of a gun is shown in the drawings in 45 which 10 designates the breech, 11 the stock, 12 the barrel and 13 the trigger. In practice, good results have been obtained by cutting the breech, stock and trigger from a relatively thick piece of cardboard, of a desired color, and by employing a cylindrical piece of wood, finished in a desired color, for the barrel. Obviously, however, other methods of construction may be resorted to for attaining the same effect, namely, that of 50 a toy firearm. As clearly shown in Fig. 2,

one end of the barrel 12 is slotted as at 14 to receive the breech 11 which is rigidly fixed thereto. Brads, nails or other securing mediums may be employed or the parts may be glued together. The opposite end of the barrel is notched as at 15. In practice, a saw-kerf is employed and wedged within such saw-kerf so as to be attached at all times to the barrel is the looped end 17 of an elastic member 16, preferably a rubber band. Substantially midway of the length of the rubber band, the same is knotted as at 18, the purpose of which will presently appear. The looped end 19 of the rubber band is caused, by stretching of the band, to engage the part of the toy symbolic of the trigger which comprises a substantially vertical notched portion 20 and an inwardly extended lip 21 which serves the purpose of a hook. In this position of the elastic member the 75 firearm is ready to be operated which is accomplished by forcing the looped end 19 of the elastic member from off the lip 21. Tension upon the elastic member being thus released, it quickly moves toward an object 80 to which aim has been directed and impinges thereagainst with an audible indication. In this connection it may be stated that the knot 18 serves to keep the parts of the elastic member together so that when hitting an 85 object a more pronounced impact may be obtained. Further the knotted portion serves to keep the elastic member beneath the barrel 12 in substantial alinement with the longitudinal axis thereof in contradistinction 90 to being upon opposite sides of the barrel. The knotted portion also serves the purpose of preventing entanglement of the elastic member since in effect two small loops are provided instead of a single large band. 95

The above described toy can be manufactured very cheaply and given away as an advertising medium, the breech of the firearm, which is flat, affording space for an advertisement.

100 It will now be apparent that I have devised a novel and useful construction which embodies the features of advantage enumerated as desirable in the statement of the invention and the above description and 105 while I have in the present instance shown and described the preferred embodiment thereof which has been found in practice to give satisfactory and reliable results, it is to be understood that the same is susceptible of 110

modification in various particulars without departing from the spirit or scope of the invention or sacrificing any of its advantages.

What I claim is:

- 10 1. A toy symbolic of a firearm including a breech, stock and barrel, an elastic member provided at each end with a looped portion, means at one end of the barrel for fixedly securing one loop of said elastic member thereto and fixed means symbolic of a trigger adjacent the stock of the firearm for temporarily retaining the other loop of said elastic member in an expanded state thereof.
- 15 2. A toy symbolic of a firearm including a breech, stock and barrel, an elastic band knotted intermediate the ends thereof to form a pair of loops, a loop accommodating notch formed at one end of the barrel to fixedly receive a loop of said elastic band and a notched portion formed in the stock of the firearm having a lip in immediate juxtaposition thereto said lip being symbolic of a trigger and being adapted to temporarily retain the other loop of said elastic band in an expanded state thereof.
- 20 3. A toy symbolic of a firearm comprising a breech and stock cut from relatively thin flat material as cardboard, said stock being provided with a notched portion having a lip in immediate juxtaposition thereto, a barrel comprising a cylindrical piece of material as wood, said barrel being partially slotted transversely at one end and slotted entirely therethrough longitudinally at the other end, the last mentioned slotted portion accommodating the said stock, means for securing said barrel and stock together, and an elastic member having a loop at each end of which one loop is fixedly secured in the transverse slot of said barrel and of which the other loop is adapted to be temporarily

retained by said lip in an expanded state of said elastic member.

4. A toy symbolic of a firearm comprising a breech and stock cut from relatively thin flat material, said stock being provided with fixed means symbolic of a trigger, a barrel comprising a cylindrical piece of material said barrel being slotted at one end to accommodate said stock, means for securing said barrel and stock together and an elastic member fixed at one end to said barrel and adapted to be temporarily retained at its other end in an expanded state thereof by said fixed means. 45 50 55

5. A toy symbolic of a firearm including a breech, stock and barrel, a notched portion provided on the underside of said stock having a depending lip in immediate juxtaposition thereto symbolic of a trigger and an elastic member fixed at one end to said barrel and adapted to be temporarily retained at its other end in an expanded state thereof by said lip. 60 65

6. A toy symbolic of a firearm including a breech, stock and barrel, a lip formed integral with said stock and depending from the underside thereof, there being a notched portion in said stock in immediate juxtaposition to said lip and an elastic member fixed at one end to said barrel and adapted to be temporarily retained at its other end in an expanded state thereof by said lip. 70 75

7. A toy symbolic of a firearm including a breech, stock and barrel, fixed means symbolic of a trigger adjacent the stock of the firearm and an elastic member fixed at one end to said barrel and adapted to be temporarily retained at its other end in an expanded state thereof by said fixed means. 80 85

In testimony whereof, I have hereunto signed my name.

ELIAS F. SLEAR.
